UNITED STATES PATENT OFFICE.

FRANK W. ROBINSON, OF READING, PENNSYLVANIA, ASSIGNOR TO NOLDE & HORST COMPANY, OF READING, PENNSYLVANIA, A CORPORATION OF PENNSYLVANIA.

KNITTING-MACHINE.

1,119,877.

Specification of Letters Patent.

Patented Dec. 8, 1914.

Application filed March 23, 1914. Serial No. 826,466.

To all whom it may concern:

Be it known that I, FRANK W. ROBINSON, a citizen of the United States, residing at Reading, in the county of Berks and State of Pennsylvania, have invented certain new and useful Improvements in Knitting-Machines, of which the following is a specification.

My invention relates to circular knitting machines such as are commonly employed for knitting seamless hosiery, and which are provided with means for introducing an extra reinforcing yarn to a portion of the needles in the knitting of certain courses. 10 The carrying of this extra yarn by a portion only of the needles employed in the knitting of a course, causes a variation in tension in the single and double thread portions of the successive courses sufficient to 20 very noticeably affect the quality of the product.

My invention consists in providing for varying the operation of the needles at the knitting point to correspond with the difference in material carried by them, as fully described in connection with the accompanying drawings, and the novel features are specifically pointed out in the claims.

Figures 1 to 5 illustrate my invention as applied to a well known type of circular knitting machine employing a rotary needle cylinder: Fig. 1 being a sectional elevation through the knitting-cam head, and indicating the means for moving said head toward or away from the needle cylinder. Fig. 2 is a separate view, developed in a straight plane, of the inside curved face of the knitting-cam head showing the knitting cams with my improvements applied thereto. 30 Fig. 3 is a corresponding plan view of one of the knitting cams. Figs. 4 and 5 are enlarged sections on the line 4—5 of Fig. 2, showing respectively the lowermost positions assumed by the needles when the knitting head is in normal position, and when it is moved away from the needle cylinder during the knitting-in of the reinforcing yarn. Figs. 6 to 8 indicate a modification of my invention applicable to the equally 40 well known circular knitting machines having fixed needle cylinders: Fig. 6 being an inside view of the cam cylinder, developed in a plane; and Figs. 7 and 8 being sectional elevations on the line 7—8 of Fig. 6, show-

ing the lowermost normal and reinforced 55 yarn knitting portions respectively.

The well known type of knitting machine indicated in Figs. 1 to 5 is more fully shown and described in Patent No. 933,443, issued Sept. 7, 1909, and I have indicated only so much as is necessary to fully explain my invention. 1 represents the needle cylinder driven in well known manner by gear wheel 2. 3 is a yarn feeding device, operated by a lever 4, actuated by a cam mechanism 5 through a link 5, to lay a reinforcing thread at determined times for part only of each revolution of the needle cylinder. This reinforcing yarn is engaged by a certain series of needles so as to provide a reinforced fabric as for instance a high spliced heel or a sole portion of a stocking. 6 is the fixed knitting-cam head carrying knitting cams as usual which operate upon the projecting butts of the needles mounted in the rotated 75 needle cylinder 1. In practice I have found that wherever this reinforcing yarn is introduced an inequality in the tension occurs that greatly impairs the appearance of the finished article. If the tension is proper for 80 the single yarn portion it is not right for the reinforced portion of the fabric. Heretofore an intermediate tension has been used which is not proper for either and results in a defective stocking.

My invention relates to mechanism for providing with a determined tension a proper draw of each loop for both single and reinforced portions of the fabric so that the texture of the finished fabric will have 90 equal tension in both parts and greatly enhance the appearance and give longer life to the stocking. To accomplish this I provide the needles that knit-in the reinforcing yarn with butts of differing height from the 95 butts of the needles operating only on the single yarn of the fabric.

Referring to the construction illustrated in Figs. 1 to 5, the long butt needles 10 are provided with butts 11 of an equal height 100 throughout their length, while the short butt needles 12 that knit-in the reinforcing yarn at determined courses, are provided with butts 13 which for a portion only are of equal height with the long butts, and 105 have a portion 14 of a greater height as determined by the difference in the draw of loop desired when the reinforcing yarn is

introduced. These needles are mounted in the rotated needle cylinder as usual and are arranged so that the series of short butt needles will always engage the reinforcing 5 yarn as operatively laid in their path at the determined portion of the fabric construction by the yarn feeding device 3. Whenever this extra yarn is introduced these short butt needles are in my improved 10 construction operated by the knitting cams to lower them deeper in the needle cylinder than the long butt needles and thus cause them to draw a longer loop as required by the additional yarn they are operating 15 on. To accomplish this I automatically move the knitting-cam head 6 toward or away from the needle cylinder as required and so shape the knitting cams that they will operate either on the low or the high 20 portions of the short butt needle 12 as determined by the location of said cam head. The cam head 6 is moved toward the needle cylinder 1 by the usual spring 20 employed in this type of knitting machine, and is 25 moved away from said cylinder a sufficient distance to cause the cams to operate upon the high portion 14 of the butts of needles 12 by the following mechanism: A lever 21 pivoted to the head 6 is connected by a rod 30 22 to a pivoted cam operated lever 23. This lever 21 is normally held raised by a spring 24 and is depressed by a cam 25 on the cam drum 26. Upon the lever 21 is mounted a wedge cam 27 which contacts with the 35 fixed base 28 upon which the head 6 is slidably mounted and is adapted to draw said head 6 away from the cylinder 1 a determined distance when the lever 21 is lowered by the cam 25 on the drum 26. 40 This cam drum which is part of the general mechanism of this type of machine also operates the yarn feed device 3, and the cams on the drum 26 may be readily timed to operate these parts in harmony. The 45 knitting cam 30 which lowers all the needles in the knitting operation is undercut as shown in Figs. 2, 4, and 5 so that only its edge portion 31 contacts with the needle butts, and the cam 32 which limits the downward throw of said needles is provided with an extension 33 having a lower-stepped portion 34. When the cam head 6 is in normal knitting position for the general run of the fabric, as shown in Fig. 4, all the needles 50 are equally lowered by the knitting cam 30-31 contacting with the even width long butts and the equal width portion of the short butts and all the butts are limited in their descent by the high portion of the extension 33 of cam 32. But when the reinforcing yarn is introduced the head 6 is automatically moved away from said needle cylinder, as shown in Fig. 5, so that the knitting cam 30 will then contact at 31 with 55 the high portion 14 of the short butt needles 12 and cause them to draw deeper into the needle cylinder 1 than the long butt needles which do not engage the reinforcing yarn, and the stepped-down portion 34 limits this longer draw of the short butt needles while 70 the high portion thereof still engages the long butt needles and prevents their being carried down by their momentum. This drawing of a loop of greater length for the part of the fabric provided with the reinforcing yarn permits of a very nice adjustment that will equalize the tension in the reinforced and non-reinforced part of the fabric and result in a finished fabric of improved texture and appearance. 80

While I have indicated my invention applied to a well known form of knitting machine in which the needle cylinder revolves and the cam head is stationary, it will readily be seen that it is equally applicable 85 to other well known types in which the needle cylinder is fixed and the cams are mounted on a revolving cylinder. And the increased draw of loop for the short butt needles may be accomplished in a different 90 manner by a corresponding change. Thus in Figs. 6 to 8 I have indicated another well known type of knitting machine in which the needle cylinder 1^a is fixed and the cam head or ring 6^a revolves. In this case the 95 butts of all the needles are of uniform height throughout their length, the short butts 13^a however being of greater height than the long butts 11^a. The usual knitting cams are used and during normal operation 100 of the machine, as shown in Fig. 7, all the needles lowered by knitting cam 30^a are limited in this downward movement by the cam 40, the long butt needles being carried there by their momentum and the short 105 butts being positively lowered. When the reinforcing yarn is introduced, as shown in Fig. 8, I introduce a cam 41 in the path of the long butt needles only, which cam positively limits their downward movement and 110 prevents their being lowered to cam 40, while the short butt needles are still being lowered to said cam 40, thus causing the short butt needles to draw a longer loop than the long butt needles as required by 115 the extra yarn, the necessary variation of the needle cylinder 1^a being simultaneously provided for.

What I claim is:-

1. In a circular knitting machine the combination with the needle cylinder of a series of adjacent needles therein adapted to knit part of the circular course, and another series of adjacent needles adapted to knit the remaining part of the circular course, one of said series having needle butts differing in height from those of the other series, means for supplying an extra yarn to one of said series of needles, needle operating mechanism movable into the path of said needles, 120
2. In a circular knitting machine the combination with the needle cylinder of a series of adjacent needles therein adapted to knit part of the circular course, and another series of adjacent needles adapted to knit the remaining part of the circular course, one of said series having needle butts differing in height from those of the other series, means for supplying an extra yarn to one of said series of needles, needle operating mechanism movable into the path of said needles, 125
3. In a circular knitting machine the combination with the needle cylinder of a series of adjacent needles therein adapted to knit part of the circular course, and another series of adjacent needles adapted to knit the remaining part of the circular course, one of said series having needle butts differing in height from those of the other series, means for supplying an extra yarn to one of said series of needles, needle operating mechanism movable into the path of said needles, 130

- and means for differently setting said mechanism so as to either operate upon all of the needles uniformly or to vary the lowering of the two series of needles at the knitting point as determined by the difference in heights of the butts.
2. In a circular knitting machine, the combination with the needle cylinder of one series of needles therein having long butts and another series having shorter butts of greater height, means for supplying an extra yarn to said short butt needles, and needle-operating means comprising a movable part adapted to vary the lowering of the two series of needles at the knitting point as determined by the difference in the heights of the butts.
3. In a circular knitting machine, the combination with the needle cylinder of one series of needles therein having long butts and another series having shorter butts of greater height, means for supplying an extra yarn to said short butt needles, and a knitting-cam mechanism adapted to normally lower all of said needles uniformly but comprising an adjustable part adapted to be moved into engagement with said short butts to vary the lowering of the same as determined by the different height thereof.
4. In a circular knitting machine, the combination with the needle cylinder of one series of needles therein having long butts and another series having shorter butts of greater height, means for supplying an extra yarn to said short butt needles, and a knitting-cam head movable in relation to said needle cylinder and adapted to normally lower all of said needles uniformly when in one position, and to lower the short butt needles below the long butt needles when in another position.
5. In a circular knitting machine, the combination with the needle cylinder of one series of needles therein having long butts and another series having shorter butts with a portion thereof of greater height, means for supplying an extra yarn to said short butt needles, and knitting cams operable either upon the high or low portion of said short butt needles.
6. In a circular knitting machine, the combination with the needle cylinder of one series of needles therein having long butts and another series having shorter butts with a portion thereof of greater height, means for supplying an extra yarn to said short butt needles, a knitting-cam head carrying a knitting cam the edge portion only of which contacts with said needle butts, and means to move said head to contact said edge portion with either the low or high portions of said short butt needles.
7. In a circular knitting machine, the combination with the needle cylinder of one series of needles therein having long butts and another series having shorter butts with a portion thereof of greater height, means for supplying an extra yarn to said short butt needles, a knitting-cam head carrying knitting cams, one of said cams having an extension to limit the lowering movement of said needles and provided with a stepped-down portion, and means to move said head to limit the short butt needles only in said stepped-down portion.
8. In a circular knitting machine, the combination with the needle cylinder of one series of needles therein having long butts and another series having shorter butts with a portion thereof of greater height, means for supplying an extra yarn to said short butt needles, a knitting-cam head carrying knitting cams, one of said cams adapted to lower the needles being recessed so that only the edge portion thereof contacts with the needle butts, and another cam having an extension to limit the lowering movement and formed with a stepped-down portion, and means to move said head to cause the edge portion of said lowering cam to contact with the high portion of said short butt needles and depress them into said stepped-down portion.
9. In a circular knitting machine, the combination with a needle cylinder of one series of needles therein having long butts and another series having shorter butts with a portion thereof of greater height, a yarn feed device for supplying an extra yarn to said short butt needles, a knitting-cam head slideable toward and away from said needle cylinder and carrying cams operable upon either the high or low portions of said short butt needles, and a cam drum having cams to simultaneously put said extra yarn feed device into operation and to move said cam head to engage the high portion of said short butt needles.

In testimony whereof I affix my signature in presence of two witnesses.

FRANK W. ROBINSON.
